UNITED STATES PATENT OFFICE.

EDWIN J. GOULD, OF SAN DIEGO, CALIFORNIA.

DIFFERENTIAL OR COMPENSATING GEARING.

1,222,097.

Specification of Letters Patent. Patented Apr. 10, 1917.

Application filed November 23, 1914. Serial No. 873,514.

To all whom it may concern:

Be it known that I, EDWIN J. GOULD, a citizen of the United States, residing at San Diego, in the county of San Diego and State 5 of California, have invented certain new and useful Improvements in Differential or Compensating Gearing, of which the following is a specification.

This invention relates to certain new and 10 useful improvements in differential or compensating gearing and it has for its objects among others to provide a simple novel form of gearing designed not to make a difference in driving but to compensate or allow 15 for the difference in distance traveled by the wheels in turning curves, and while permitting this, to drive as near as possible as would a stiff axle, by applying the power equally to each wheel the one wheel being 20 allowed to rotate faster than the other wheel.

Other objects and advantages of the invention will hereinafter appear and the novel features thereof will be particularly pointed out in the appended claims.

25 The invention is clearly illustrated in the accompanying drawings which, with the numerals of reference marked thereon, form a part of this specification, and in which—

Figure 1 is a substantially central trans- 30 verse section as on the line 1—1 of Fig. 2 showing the arrangement of parts in accordance with my present invention.

Fig. 2 is a section at right angles to Fig. 1 with parts in elevation and portions broken 35 away.

Like numerals of reference indicate like parts throughout the different views.

Referring to the drawings,

1, 1^a designate the adjacent ends of the 40 axle sections, 2 an eccentric fast on the axle section 1^a, while 3 is a spur pinion on the axle section 1.

4 is an internally toothed gear and eccentric guide combined, preferably in one piece 45 or at least arranged to move as one. If desired, ball bearings, as at 5, may be interposed between the eccentric 2 and the guide 4, as seen in Figs. 1 and 2.

6 is a casing inclosing the afore-named 50 parts, said casing having a radial slot 7 in its opposite walls, as seen in both views, and working in this slot in the pin or bolt 8 ex- tending through the internally toothed gear and eccentric guide 4, as seen in Figs. 1 and 55 2, the bolt being designed to travel in and

out in said slot as it is moved by the eccentric.

With the parts constructed and arranged substantially as above described, and with the understanding that the shafts 1 and 1^a 60 are attached to the rear wheels of the vehicle, the operation will be readily understood when taken in connection with the annexed drawings. Power is applied to the axle section 1^a. Suppose the casing 6 re- 65 mains stationary and the axle section 1^a to which the eccentric 2 is fastened is rotated in the direction of the arrow thereon in Fig. 2, the change of bulge or the long center of the eccentric in its position with relation to 70 the bearing of the eccentric or guide 4 is changed in its relation to the casing 6 as to cause the pin 8 to travel in the slot 7, the motion of the eccentric being circular and the bearing or eccentric guide being given a cir- 75 cular swinging motion, which motion tends to make it travel around the pinion 3, but being prevented from actual travel around said pinion by the pin 8, the pinion will be necessarily rotated in the direction of the 80 arrow thereon in Fig. 2 or in an opposite direction from that of the eccentric; this is a perfect differential action. When the eccentric is not rotated but motion comes from the axle section carrying the pinion, the 85 action is similar, but directions are reversed. In other words, the two axle sections, one bearing the eccentric and the other bearing the pinion cannot travel in the same direction in the casing, but travel in opposite di- 90 rections. The eccentric travels in the eccentric guide by what may be termed a slipping motion, while the pinion can travel only in a rolling motion because of the teeth.

The eccentric guide, as will be best under- 95 stood upon reference to Fig. 2, consists of an internally toothed gear without a center, or a hollow rim toothed internally for half its width and half being smooth for a bearing. The teeth may be straight spur teeth or arranged in the form of a spiral or worm. I have obtained best results from the latter, as the action in driving one wheel independent of the traction of the other is more certain. It will be noted that the internal gear is always in its true position, being so held by the eccentric. 100 105

In operation the internal gear has an oscil- lating as well as a rotary movement. The two gears are held in mesh by the eccentric 110

and actuated by change in position of the eccentric acting upon the eccentric guide 4.

My present invention is distinguished from the present form of differential gears 5 in that while in the usual form the power goes to the wheel with the least resistance and in turning curves this, of course, would be the outside wheel, while in the present construction such action does not take place 10 because of the friction within itself, and this is especially so when spiral internal teeth and pinion are used. My present device is not designed to run wheels at different speeds at all times or to apply more 15 power to one than to the other because the diameter of the pinion on one axle section and the eccentric on the other are slightly different, this slight difference in size being taken care of in actual practice by the friction 20 of the eccentric in its bearing and the application of power to each axle section, both in running straight and turning, being practically equal.

A device constructed in accordance with 25 my present invention is what may be termed an interlocking driving device, which releases and adjusts itself to the difference in distance traveled by the wheels on curves and around corners by the action of the 30 toothed gear wheels and the eccentric, the pinion and internal gear guide having a rolling motion in relation to each other because of the teeth and the eccentric and its bearing having a sliding motion relative to each 35 other, and the internal gear and eccentric bearing being rigid with each other, the one motion must take place to admit of the other. In driving straight, the whole mechanism revolves with the axle but the eccentric and gear stand in relation to each other, while in turning curves they move very 40 slowly in their relative positions as the difference in distance traveled by the wheels is in any case slight.

45 When ball bearings are introduced between the eccentric and eccentric guide, it constitutes a good reverse gear having much strength because of the many teeth engaged at one time between the internal gear and pinion. This also would hold true in the 50 use of the device in transmissions of the planetary type.

The internal gear may be secured within the casing in any suitable manner so long 55 as it is allowed to oscillate in the casing without rotating therein.

Modifications in details may be resorted to without departing from the spirit of the invention or sacrificing any of its advantages.

60 What is claimed as new is:—

1. A transmission gear comprising in combination axle sections, a gear and an eccentric adapted to be mounted on said axle sections and means coöperating with said

gear and eccentric to constitute an interlocking driving device.

2. A transmission gear comprising in combination a gear and an eccentric mounted for movement independent of each other and 70 means coöperating with and serving to constitute with said gear and eccentric an interlocking driving device.

3. A transmission gear comprising in combination a gear and an eccentric adapted 75 to be mounted on coaxial, independent axle sections, and means coöperating with said gear and eccentric for causing them to have different motions in unison.

4. A transmission gear embodying axle 80 sections, an eccentric fast upon one section, a pinion on the other section and an internally toothed gear meshing with said pinion and forming a guide for the eccentric.

5. A transmission gear embodying axle 85 sections, an eccentric fast upon one section, a pinion fast upon the other section and an internally toothed gear meshing with said pinion and forming a guide for the eccentric and a casing in which said internal 90 gear is radially movable.

6. A transmission gear comprising an eccentric, a bearing therefor, a pinion and means to cause the eccentric and its bearing to have a sliding motion relative to each 95 other.

7. A transmission gear comprising an eccentric, a bearing therefor, a pinion and means to cause the eccentric and its bearing to have a sliding motion relative to each 100 other, said pinion and eccentric moving in opposite directions, and the bearing movable radially.

8. In a differential gear, a casing having radial slots, an internally toothed gear and 105 eccentric guide in said casing, means carried thereby movable in said slots permitting radial movement of the latter, a pinion with in said gear and guide engageable with the said gear, and an eccentric within said gear 110 and guide movable in a direction opposite to that of the pinion.

9. In a transmission gear, a casing having radial slots, an internally toothed gear and eccentric guide having pins, radially movable 115 in said slots permitting radial movement of said guide, said gear having an untoothed portion, an axle section, an eccentric thereon having bearing on said untoothed portion, a second axle section, and a pinion 120 thereon having engagement with the teeth of said gear.

10. In transmission gearing, two axle sections, an eccentric carried by one, a pinion carried by the other and an internal gear 125 and eccentric guide, said eccentric having a slipping motion within the guide and the pinion a rolling motion within the gear.

11. In transmission gear, a casing, an eccentric therein for attachment to an axle 130

section, a pinion in said casing attachable to another axle section, an internally toothed gear and eccentric guide combined receiving said eccentric and pinion and interengaging 5 means on the casing and guide permitting radial movement of the latter.

12. In transmission gear, a casing, an eccentric guide therein internally toothed, a pinion in said casing engaging the teeth of 10 said guide, an eccentric in said casing with-

in said guide, and means permitting said guide to have an oscillatory and a rotary movement.

In testimony whereof I affix my signature in the presence of two witnesses.

EDWIN J. GOULD.
